LAVATORY WASTE

Roy H. Zinkil, Oak Park, and Eugene W. Mar-
chand, Maywood, Ill., assignors to Crane Co.,
Chicago, Ill., a corporation of Illinois

Application May 26, 1934, Serial No. 727,598

24 Claims. (Cl. 4—199)

This invention relates to lavatory waste constructions and to waste plugs for use in such constructions.

A primary object of the invention is to provide a lavatory with waste equipment which will afford an unobstructed discharge passage from the waste outlet of the lavatory when the waste plug thereof is raised from its seat, and which will be efficient, convenient, easily operable and reliable after long periods of service.

In a construction embodying the invention, the waste plug, which may be operated from a conveniently located lever, plunger or other device through concealed operating connections, is of the tubular strainer type, i. e. the waste plug is of the type through which discharge takes place when the waste plug is raised from its seat; this type of waste plug being desired to obtain an unobstructed discharge passage from the lavatory outlet.

Waste plugs of the type referred to have frequently been difficult to operate, in prior constructions, on account of binding or sticking of the waste plug in the spud or waste outlet tube in which it is fitted. Such binding has been due in some instances to frictional resistance, increased by corrosion of the parts or by the caking of soapy matter adhering to the parts. But the most serious cause of binding has been the accumulation and packing of hair, lint or the like between the walls of the waste plug and spud. Hair is especially troublesome in this respect. Such material collecting between the waste plug and spud tends to pack tightly, creating a resistance to the proper operation of the waste plug and in course of time rendering it extremely difficult to effect the full opening and closing movements of the waste plug. Difficulty in operating the waste plug is very annoying, and further the binding of the waste plug is objectionable because it imposes undue strain on the operating means, which may result in breakage or binding of the operative connections and thus call for repairs in addition to the needed cleaning out of the waste plug and spud.

The difficulties mentioned are obviated or greatly reduced by the present invention, which provides a construction of the waste plug or of the spud in which it is fitted whereby hairs and bits of lint contained in the discharging waste water, or such of them as may not pass into the interior of the waste plug, are caused to be washed down between the plug and spud through longitudinal washout channels, and are discharged with the wash water to the waste pipe. With the

constructions herein described, the space between the waste plug and spud is kept substantially clear of hair, lint or the like, or at least free of such accumulations as would offer material resistance to the proper operation of the waste plug. Moreover these constructions minimize or reduce frictional resistance and opportunity for binding from corrosion or other causes.

A further feature of the invention is the provision of a lavatory waste construction having the above indicated feature of improvement and a type of operating means whereby there is no obstruction of the passage to the waste pipe.

The invention includes a novel waste plug per se, and a form of construction thereof which in addition to its advantages in use is also of advantage from the standpoint of manufacture. The invention further includes a novel method of manufacturing such waste plugs.

The invention will be described by reference to the accompanying drawings, and will be particularly pointed out and defined by the claims following the description.

In said drawings:

Fig. 1 is a sectional view of a portion of a lavatory, showing one practicable form of waste construction as a whole embodying the invention.

Fig. 2 is a detail section at right angles to Fig. 1 showing the manually operated means for working the lift rod and plug engaging means shown in Fig. 1.

Fig. 3 is a side elevation of the waste plug employed in Fig. 1, said waste plug being claimed herein per se.

Fig. 4 is a horizontal section taken through the waste plug and spud on the line 4—4 of Fig. 1, showing the lift yoke for the waste plug in top plan view.

Fig. 5 is a similar section taken on the line 5—5 of Fig. 1.

Figs. 6 and 7 show a tube from which tubular waste plug bodies are to be formed, Fig. 6 being an end view and Fig. 7 a side elevation. The production of such a tube comprises a step or steps in the method herein described of manufacturing the waste plug.

Figs. 8 and 9 show a tubular waste plug body formed from the aforesaid tube, Fig. 8 being a top plan view thereof and Fig. 9 a central vertical section.

Fig. 10 is a central vertical section of the cap and tubular body of the waste plug ready for assembly.

Fig. 11 is a bottom plan view of the tubular

plug body, showing the construction of the lower end thereof.

Fig. 12 is a cross section of a waste plug and spud, representing an embodiment of the invention in which both the waste plug and spud are constructed to provide longitudinal guide ribs and washout channels.

Fig. 13 is a longitudinal section of a construction in which only the spud is constructed to provide the guide ribs and washout channels.

Fig. 14 is a cross section of the construction shown in Fig. 13.

Fig. 15 is a side elevation of a waste plug similar to that shown in Fig. 3 except that the guide ribs extend spirally instead of parallel with the axis of the plug.

Fig. 16 is a side elevation of the lower end portion of a waste plug of the type shown in Fig. 3 but having a different lower end construction adapted for a different form of lift device.

In Fig. 1, the numeral 1 denotes a lavatory having a waste outlet opening defined by the annular plug seat 2 at the upper end of the spud or waste outlet tube 3 which is inserted through the usual waste hole in the bottom wall of the lavatory bowl and retained by its flange 4 seated on the upper side of said wall in the depression around the waste hole. The lavatory has in its back wall an overflow outlet 5 and is constructed to provide an overflow chamber 6. The spud 3 extends through the bottom wall of the overflow chamber and is joined by the coupling 7 with the waste pipe 8. A water tight joint between the spud and bottom wall 9 of the overflow chamber is provided by the packing 10. Diametrically opposite openings 11 in the spud permit discharge of water from the overflow chamber through the spud to the waste pipe.

The waste outlet of the lavatory is controlled by a waste plug 12 slidably mounted in the spud, said waste plug comprising a reticulated tubular body having a head or cap 13 of larger diameter than the depending tubular part and which fits in the plug seat 2 to close the waste outlet. Upon raising the waste plug from its seat, water discharges from the lavatory through the plug, passing through the slots or water inlet openings 14 thereof into the interior of the plug and discharging from the lower open end thereof.

The waste plug is raised and lowered by manually operated means through concealed operating connections which in this instance are housed in the overflow chamber. The specific operating means shown is of the desirable type disclosed in United States patent to Zinkil and Osterhage No. 1,816,458 of July 28, 1931. This operating means comprises a vertically movable lift arm having rigid therewith a horizontally disposed yoke 15 which straddles the waste plug, engaging portions thereof exposed through the diametrically opposite openings 11 on the spud. As indicated by dotted lines in Fig. 1, the openings 11 are of sufficient height to allow the extent of vertical movement of the yoke 15 which is required to elevate the waste plug to a position exposing the full lengths of its slots 14 above the plug seat 2.

The slots or water inlet openings of the waste plug are of such number and dimensions as to provide a water inlet area as great as the discharge or outlet area of waste plug. By employing a waste plug of this tubular type, open at its lower end, and operated by means engaging the external sides of the waste plug, an unobstructed

water discharge passage from the waste outlet opening of the lavatory is obtained.

The illustrative structure shown in Fig. 1, and as thus far described, is similar to that disclosed in the aforesaid patent except in respect to the waste plug 12 of said illustrative structure, which waste plug is of a novel construction affording pronounced advantages.

As shown in various figures of the drawings, the waste plug 12 is constructed to provide longitudinal guide ribs 16, the slots 14 being formed between the ribs in the upper half of the plug. The guide ribs 16 extend from the head of the plug to its lower end, thereby providing water channels 17 in line with the slots 14, said water channels 17 extending to the lower end of the plug and having open or unobstructed discharge ends. Consequently when the waste plug is raised to open position, the water will discharge from the lavatory not only through the plug by way of the slots 14 but also between the plug and spud by way of the water channels 17, with the effect of pronounced tendency of washing down and discharging below the plug all hairs, bits of lint or the like that fail to pass out through the slots 14, thus keeping the space between the plug and spud clear of accumulations which would interfere with or create resistance to the movement of the plug. In other words the waste plug freely passes hair and lint that would in ordinary constructions be retained between the plug and spud. Moreover the plug is operable with less friction than in the case of a plug having a plain or unribbed cylindrical surface, and the opportunity for binding or sticking of the plug in the spud, from corrosion or caking of soapy matter is minimized.

A similar result would be obtainable with the use of a waste plug having a plain cylindrical exterior surface by employing a spud having its interior surface longitudinally ribbed to provide water channels in line with the slots or water inlet openings of the plug and extending below the plug and open at both the upper and lower ends, so as to provide for the flow of water downwardly between the plug and spud in a plurality of courses from the inlet slots as well as for flow through the plug. Such a construction is represented in Figs. 13 and 14, while in Fig. 12 a construction is shown in which both the waste plug and spud are formed with guide ribs and water washout channels.

In the specific construction of the waste plug 12 shown in Figs. 1 to 11 of the drawings, the slots 14 of the plug are provided wholly by the spaces or interstices between the ribs 16. The slots may be of greater width than the ribs, so as to provide a relatively large area for admission of water to the interior of the plug. As shown more clearly in Figs. 4 and 6, the ribs may be formed so that the full width of the interstices between the outer faces of the ribs is utilized for the slots. The plug 12 constructed as shown comprises the head 13, the circular series of spaced ribs 16, and the tubular lower part 18 having the said ribs formed thereon and projecting above the same, said tubular lower part of the plug being joined with the head by the upwardly projecting extensions of the ribs.

As shown more clearly in Fig. 10, the plug may be constructed in two parts, namely a tubular body member comprising the part 18 having the ribs 16 formed thereon and projecting above the same, and the separate cap or head 13 which is suitably secured to the upper end of said body member, i. e. to the upper ends of the project-

ing ribs 16. The cap may be secured to the body member in any suitable manner, for instance by screwing it thereon or brazing it thereto. As shown the upper ends of the ribs 16 are entered 5 into an annular groove 19 formed in the under-side of the cap. A small circumferential groove 20 is formed in the exterior surfaces of the ribs near their upper extremities, and the outer lower edge portion 21 of the cap is spun or swaged 10 into the groove 20 for securely uniting the cap with the body member.

The construction of the plug in two pieces as just described is desirable as an incident of availing of the novel manufacturing method 15 hereinafter described; however it will be apparent that the plug could be cast or otherwise made in one piece, including the cap, if desired.

Near its lower end the plug 12 is formed with a circumferential groove 22 for engagement by 20 the arms of the operating yoke 15. This groove 22 is formed in and across the ribs 16, the groove being interrupted by the channels between the ribs. To facilitate insertion of the plug into the yoke, the plug is formed at its lower end with 25 diametrically opposite insert flats 23, consisting of flat beveled portions the planes of which intersect the planes of diametrically opposite channels 17 below the circumferential groove 22. These insert flats 23 are shown more clearly in 30 Figs. 1 and 11. They permit the lower end of the plug to be forced between the arms of the yoke 15, slightly springing said arms, which will then snap into engagement with the groove 22. At diametrically opposite points midway between 35 the insert flats the portion of the plug having the groove 22 is provided with locking flats 24, i. e. flat surfaces on the ground of said groove. Thus the plug after it is inserted in the yoke 15 can be given a quarter turn, whereupon the yoke arms will snap into engagement with the locking 40 flats 24, as shown more clearly in Fig. 5, thus holding the plug properly assembled in connection with the operating means, preventing it from becoming disengaged from the lavatory. In addition to the insert bevels 23, the entire lower 45 extremity of the plug is preferably given a short tapered form by beveling the lower ends of all the ribs as indicated at 25.

The specific operating means shown as an illustrative example in Fig. 1 (being that disclosed 50 in the aforesaid Zinkil and Osterhage patent) is briefly explained thus: The yoke 15 is carried by an arm 26 rigidly attached to the vertical rod 27 which is adjustably secured in the tubular lift rod 28 guided for vertical motion 55 in the guide 29. The rod 28 is provided at its upper end with a hook 30 which engages the offset or cranked portion 31 of a crank shaft 32 mounted in a member 33 on the top of the back portion of the lavatory structure, which member 60 is covered by the removable cap 34. The ends of the crank shaft 32 are integrally or rigidly connected with the ends of the arms 35 of a bifurcated lever having a handle 36. When the handle 36 is in the horizontal position shown in Fig. 2, 65 the crank 31 projects downward as shown in Fig. 1 and the waste plug is in its seated or closed position. By swinging the handle 36 from the position shown to a horizontal position at the opposite side 70 of the housing member 33, the lift rod is raised a sufficient distance to raise the waste plug to its full open position. The crank 31 is at an angle slightly less than 90° from the handle. Accordingly when the handle is thrown to the position 75 to raise the waste plug, the crank will move

slightly past a vertical or dead center position, so that the weight of the waste plug and its operating connections will hold the handle in the open position, preventing accidental closing movement of the waste plug. On the other hand 5 the handle can be easily swung from open to closed position to effect the closing of the waste outlet.

By the employment of a waste plug of the construction described, in connection with operating 10 equipment whereby the plug is operated from a conveniently located manual device through operating connections located out of sight and operatively connected with the plug by means engaging the plug laterally, we provide a highly ad- 15 vantageous lavatory waste construction, characterized by an unobstructed waste outlet connection, and by a conveniently and easily operable apparatus which will always be reliable to effect the full opening and closing of the waste 20 outlet.

Reference will now be made to a novel method of manufacturing waste plugs of the tubular strainer type, by which method plugs of the construction or character herein described can be 25 produced in a practicable, efficient and economical manner. This involves constructing the plugs in two pieces as already explained. The cap 13 can be cheaply produced in quantities by any desired pressing or stamping operation. The body member for assembly with the cap is produced as follows: First we provide a longitudinally ribbed tube. A tube of this character is shown in Figs. 6 and 7, being designated by the numeral 37. Such a tube may be made by cut- 35 ting the longitudinal grooves therein, or it may be produced by any one of a number of methods of forming fluted tubing. This tube is then cut into sections of the proper length for the tubular plug bodies. Each section is then bored 40 in the upper half to the bottom of the ribs 16, thereby leaving openings between the ribs. Thus the tubular plug body is produced in the form shown in Figs. 8 and 9, except for the machining required to form the groove 22, insert flats 45 23, locking flats 24 and bevels 25 at the lower extremities of the ribs. If the plug is to be used with operating means employing a lift yoke, the machining operations for forming said groove 22, flats 23, 24 and bevels 25 are performed, and 50 the finished body is then assembled and united with the cap as already described.

As hereinbefore indicated, it is within the contemplation of the present invention to provide a lavatory waste construction having either the 55 waste plug or the spud or both formed with guide ribs and washout channels arranged for the described function of permitting discharge of waste water around the plug so as to keep the space between the plug and spud sufficiently clear of 60 accumulations of hair or lint and the like to prevent binding of the plug or interference with its proper operation.

A construction in which the waste plug has a plain cylindrical exterior surface and is slidably 65 mounted in an internally longitudinally ribbed spud which provides the washout channels, is represented in Figs. 13 and 14. In these figures, 40 designates the plug, 41 the water inlet slots thereof, 42 the spud, 43 the internal longitudinal 70 guide ribs of the spud, and 44 the water washout channels which are opposite or in communication with the slots 41 and extend below the bottom of the plug. The lower part of the plug may be reduced in exterior diameter to provide the an- 75

nular shoulder 45 for engagement by a lift yoke. The lower end of the plug is shown formed with diametrically opposite insert bevels 46. At intermediate diametrically opposite points are the 5 square holes 47 which function similarly to locking flats for engagement by yoke arms.

A construction in which both the waste plug and spud are formed to provide longitudinal guide ribs and washout channels is shown in Fig. 12. 10 In this figure, the waste plug may be of the same construction as in Figs. 1 to 11; namely it comprises the lower tubular part 18 having the guide ribs 16 formed thereon and extending thereupon, and the water inlet slots 14 being between the 15 ribs in the upper part of the plug. The spud in Fig. 12 is designated by the numeral 42, its internal ribs by 43 and its channels by the numeral 44.

In Figs. 12 and 14, the spud is shown having 20 twice as many grooves or channels as the number of water inlet slots of the plug, and the spacing of said grooves or channels is such that each rib of the plug will bear on one or two ribs of the spud. As shown in Fig. 12, each rib of the plug 25 bears on one rib of the spud, so that each water inlet slot of the plug is opposite two channels of the spud, it being understood that the plug is held in this relation to the spud by engagement with the operating means. However each rib of 30 the plug could bear on two ribs of the spud, as shown in Fig. 14. Also, if preferred, the spud could have the same number of channels as the number of water inlet grooves in the plug, in which event the said water inlet slots should be 35 opposite the said channels.

It is within the purview of the invention to arrange the guide ribs and washout channels, whether on the waste plug or in the spud, otherwise than vertical or parallel with the axis of the 40 waste plug. For example, Fig. 15 shows a waste plug of a construction identical with that shown in Figs. 1 to 11 except that the ribs and channels in Fig. 15 extend spirally or at an inclination to the vertical. In Fig. 15, 12^a designates the plug 45 as a whole, 13^a the head or cap thereof, 16^a its longitudinal ribs, 14^a its water inlet slots between the ribs on the upper part of the plug, 17^a the water washout channels between the ribs on the lower part of the plug, 22^a the yoke groove, and 50 24^a the insert flats or bevels.

A waste plug constructed as in Fig. 15 will function substantially or nearly as well as the waste plug shown in Figs. 1 and 3, so far as concerns the provision for washout of hair and lint 55 by discharge of waste water through a plurality of channels around the plug; and, while it may offer a somewhat greater frictional resistance to movement than the plug shown in Figs. 1 and 3, it will have on the other hand an advantage in 60 tending to keep all parts of the coating surface of the spud quite clean by the movement of the inclined ribs over said surface. A waste plug of the character shown in Fig. 15 may be used either with a plain spud as in Fig. 1 or with a spud internally ribbed as in Figs. 12 and 14, the latter being an excellent combination.

The features of the yoke groove, insert flats and locking flats described with reference to the waste plug shown in Figs. 1 to 11 are employed 70 where the waste plug is operated by a lift yoke, which is a desirable operating device particularly in a construction having the operating connections housed in the overflow chamber. However the invention in its broader aspects is not intended to be limited to use of a lift yoke nor to any 75

particular type of operating means nor to an arrangement of the operating means in the overflow chamber. It is possible without obstructing the discharge passage below the waste plug to operate the plug by means other than a lift yoke, for instance by means engaging the waste plug at one side only. Such operating means may comprise a lift arm rigid with a vertically movable operating rod, or a lever arm or the like, in which case the lower end portion of the waste 5 plug, instead of being formed with the aforesaid adjunctive features for use with a lift yoke, may be formed with a bayonet slot for engagement by the end of such lift arm or lever arm. An illustrative construction is shown in Fig. 16, wherein 10 50 designates a waste plug of the type shown in Figs. 1 to 11 but having its lower portion formed with a bayonet slot 51. The end of a lift arm engaging said bayonet slot is indicated in dotted lines at 52 in Fig. 16. It is also possible to extend 15 the waste plug below the bottom wall of the overflow chamber and to connect it with operating means arranged below the lavatory but outside of such chamber. In this case the waste plug would be connected with the operating means 20 through a lift yoke, lift arm, lever or the like housed in a boxing or housing incorporated in the waste line between the outlet chamber and the waste pipe 8.

From the foregoing it will be understood that 25 the invention is susceptible of various forms of embodiment. The term "lavatory" is to be understood as including sinks, tubs and other receptacles to which the invention may be applicable.

What we claim as our invention, and desire to 30 secure by Letters Patent, is:

1. A lavatory waste construction comprising a waste outlet tube, a waste plug slidably mounted therein comprising a longitudinally ribbed tubular body having a head to seat over the upper end of the waste tube and having vertical slots in the upper part thereof between the ribs thereof, said body having a circumferential groove in the ribs thereof below the said slots, a lift yoke engaging 40 said circumferential groove, said tube having opposite openings to accommodate said yoke and its movement, operating means carrying said yoke, the lavatory being constructed with an overflow chamber housing the said waste outlet 45 tube and operating means and yoke, and exposed manually operable means for operating said operating means.

2. A lavatory waste construction comprising a waste outlet tube, a waste plug slidably mounted 55 therein comprising a longitudinally ribbed tubular body having a head to seat over the upper end of the waste tube and having vertical slots in the upper part thereof between the ribs thereof, said body having a circumferential groove in the ribs thereof below the said slots, a lift yoke engaging 60 said circumferential groove, said tube having opposite openings to accommodate said yoke and its movement, a vertically disposed vertically movable lift rod having a rigid arm carrying said yoke, the lavatory being constructed with an overflow chamber enclosing said waste outlet 65 tube and lift rod and yoke, and said lift rod being guided and extending through the back part of the lavatory slab and having means on its upper 70 end for raising and lowering the lift rod.

3. A lavatory waste construction comprising a waste outlet tube, a waste plug of the tubular strainer type slidably mounted therein, one or both of said members having longitudinal guide 75

- ribs, said ribs providing channels whereby when the waste plug is in discharging position water not only discharges through the plug but also exteriorly thereof through said channels, concealed operating means for raising and lowering the waste plug operatively connected therewith laterally thereof below its water inlet openings, whereby the discharge passage through the plug and tube is unobstructed, the tube being laterally cut away to accommodate the connection between the plug and operating means and allow the movement thereof required to operate the plug, and exposed manually operated means for operating said operating means.
4. A lavatory waste construction comprising a waste outlet tube, a waste plug of the tubular strainer type slidably mounted therein, one or both of said members having longitudinal guide ribs, said ribs providing channels whereby when the waste plug is in discharging position water not only discharges through the tubular part of the plug but also exteriorly thereof through said channels, concealed operating means for raising and lowering the waste plug comprising a vertically movable horizontally disposed yoke embracing and connected with the waste plug below its water inlet openings, the waste outlet tube having lateral openings to accommodate the yoke and its movement, and exposed manually operated means for operating said operating means.
5. A lavatory waste construction comprising a waste outlet tube, a waste plug of the tubular strainer type slidably mounted therein, one or both of said members having longitudinal guide ribs, said ribs providing channels whereby when the waste plug is in discharging position water not only discharges through the tubular part of the plug but also exteriorly thereof through said channels, concealed operating means for raising and lowering the waste plug operatively connected therewith laterally below the water inlet openings of the plug, the tube being laterally cut away to accommodate the connection between the plug and operating means and allow the movement thereof required to operate the plug, and exposed manually operated means for operating said operating means.
6. A lavatory waste construction comprising a waste outlet tube, a waste plug of the tubular strainer type slidably mounted therein, one or both of said members having longitudinal guide ribs, said ribs providing channels whereby when the waste plug is in discharging position water not only discharges through the plug but also exteriorly thereof through said channels, said plug having a circumferential groove below its water inlet openings, a lift yoke engaging said groove, the plug being formed at its lower end with opposite bevels to permit its insertion into the yoke, and means for operating the lift yoke.
7. A lavatory waste construction comprising a waste outlet tube, a waste plug slidably mounted therein comprising a longitudinally ribbed tubular body having a head to seat over the upper end of the waste tube and having vertical slots in the upper part thereof between the ribs thereof, said body having a circumferential groove in the ribs thereof below the said slots, and a lift yoke engaging said circumferential groove, said tube having opposite openings to accommodate said yoke and its movement.
8. A lavatory waste construction comprising a waste outlet tube and a waste plug of the tubular strainer type slidably mounted therein, one of
- said members having longitudinal guide ribs which provide the entire surface for sliding engagement with the other member.
9. A waste plug of the tubular strainer type having longitudinal guide ribs providing washout channels in the exterior surface of the plug.
10. A lavatory spud having internal longitudinal guide ribs providing washout channels in the interior surface of the spud.
11. A waste plug comprising a head and a tubular body depending therefrom having an upper part provided with water inlet openings and an imperforate lower part, said body having longitudinal guide ribs extending from the head to the lower end providing washout channels in the exterior surface of the plug.
12. A waste plug of the tubular strainer type having longitudinal slots providing water inlet openings and external longitudinal water channels extending from said openings to the lower end of the plug.
13. A waste plug of the tubular strainer type having longitudinal slots providing water inlet openings and external longitudinal water channels extending from said openings to the lower end of the plug, the said slots, ribs and channels being spirally arranged.
14. A waste plug comprising a head and a tubular body depending therefrom, said tubular body comprising a series of spaced longitudinal ribs and an imperforate cylindrical lower part spaced from the head and connected therewith by said ribs, the spaces between the ribs providing water inlet slots in the upper part of the plug and external channels aligned with said slots on the lower part of the plug.
15. A waste plug comprising a head and a tubular body depending therefrom having a series of vertical slots therein and external channels aligned with said slots and extending below the same and having open lower ends, said plug being formed below said slots with means for operative engagement by a lifting member.
16. A waste plug of the tubular strainer type having longitudinal guide ribs, said guide ribs being circumferentially grooved for engagement by a lift yoke below the water inlet openings of the plug.
17. A waste plug of the tubular strainer type having longitudinal guide ribs, said guide ribs being circumferentially grooved for engagement by a lift yoke below the water inlet openings of the plug, the lower end of the plug being formed with opposite beveled portions providing insert flats.
18. A waste plug of the tubular strainer type having longitudinal guide ribs, said guide ribs being circumferentially grooved for engagement by a lift yoke below the water inlet openings of the plug, the lower end of the plug being formed with opposite beveled portions providing insert flats, and the circumferentially grooved part of the plug being formed with diametrically opposite locking flats between the insert flats.
19. A lavatory waste construction comprising a waste outlet tube and a waste plug of the tubular strainer type slidably mounted therein, one or both of said members having longitudinal guide ribs, said ribs providing washout channels between the two members, whereby when the waste plug is in discharging position water discharges into the waste outlet tube not only through the plug but also exteriorly thereof through said channels.
20. A lavatory waste construction comprising

a waste outlet tube and a waste plug of the tubular strainer type slidably mounted therein, said plug having longitudinal guide ribs providing washout channels between the plug and tube, 5 whereby when the waste plug is in discharging position water discharges into the waste outlet tube not only through the plug but also exteriorly thereof through said channels.

21. A lavatory waste construction comprising a 10 waste outlet tube and a waste plug of the tubular strainer type slidably mounted therein, said tube having longitudinal guide ribs providing washout channels between the plug and tube, whereby when the waste plug is in discharging 15 position water discharges into the waste outlet tube not only through the plug but also exteriorly thereof through said channels.

22. A lavatory waste construction comprising a 20 waste outlet tube and a waste plug of the tubular strainer type slidably mounted therein, said members having longitudinal guide ribs, the ribs of the plug bearing on ribs of the tube, said ribs providing washout channels between the two

members, whereby when the waste plug is in discharging position water discharges into the waste outlet tube not only through the plug but also exteriorly thereof through said channels.

23. A lavatory waste construction comprising a 5 waste outlet tube and a waste plug of the tubular strainer type slidably mounted therein, each of said members having longitudinal guide ribs providing washout channels between the two members, there being twice as many ribs and grooves 10 in the tube as in the plug, each rib of the plug bearing on one rib of the tube.

24. A lavatory waste construction comprising a 15 waste outlet tube and a waste plug of the tubular strainer type slidably mounted therein, each of 15 said members having longitudinal guide ribs providing washout channels between the two members, the ribs and grooves of one of said members being parallel with the axis of the tube and the ribs and grooves of the other member being 20 spirally arranged.

ROY H. ZINKIL.
EUGENE W. MARCHAND.
